UNITED STATES PATENT OFFICE.

CHARLES E. TEPPER, OF ROCHESTER, NEW YORK.

CORE-MAKING MACHINE.

1,269,230.

Specification of Letters Patent. Patented June 11, 1918.

Application filed January 21, 1918. Serial No. 213,103.

To all whom it may concern:

Be it known that I, CHARLES E. TEPPER, a citizen of the United States, and resident of Rochester, in the county of Monroe and State of New York, have invented certain new and useful Improvements in Core-Making Machines, of which the following is a specification.

The present invention relates to core making machines, and more particularly to the type in which the core box and the bench are supported, so that one is guided toward and from the other, an object of this invention being to provide for guiding the core box toward and from the bench in such a manner that all lateral play of the core box may be eliminated, notwithstanding wear on the parts of the machine. Another object of the invention is to support the core box in such a manner that it may be swung about two horizontal axes at right angles to each other, one of said axes being in rear of the core box, so that the core box may be supported at any desired angle with reference to the bench.

To these and other ends the invention consists of certain parts and combinations of parts, all of which will be hereinafter described, the novel features being pointed out 30 in the appended claims.

In the drawings:

Fig. 1 is a side view of a machine constructed in accordance with this invention;

Fig. 2 is a plan view of the same machine; Fig. 3 shows the machine in front elevation;

Fig. 4 shows the core box inverted for receiving the sand;

Fig. 5 is a section on the line 5—5, Fig. 2; and

Fig. 6 is a section on the line 6—6, Fig. 2.

It has been suggested prior to this invention that the core box and the bench be supported in such a manner that one of such parts may move toward and from the other on guides. These guides, however, have been so constructed that the sand used in the molding operations increases the wearing action to such an extent that eventually the guided part has so much lateral play that the machine becomes useless, and must be thrown away or new guiding parts provided. According to this invention the wear in the guide parts is taken up in such a manner that an old machine operates as well as a new and this without the substitution of new

guiding parts, when the old guides have worn.

Referring more particularly to the drawings where one embodiment of the invention is shown, 1 indicates a base frame to the upper face of which the bench plate 2 is secured preferably by bolts 3. This manner of securing the bench plate 2 to the base frame 1 permits the bench plate to have its plane with reference to the base frame changed, so that it may lie in an inclined position on the base frame, this being sometimes desirable when the core, instead of projecting upright, projects at an inclination from the bench plate. At the rear of the bench plate 2 a rod 4 projects upwardly, and in rear of the guide rod 4 a guide rod 5 is provided. On the guide rod 4 a frame 6 is movable, said frame having a tubular portion 7 surrounding the guide rod 4 and having Babbitt bushings 8 at opposite ends. To the frame 6 a flexible connector 9 is secured at one end and passes up about a pulley 10 having a weight 11 at its free end acting as a counterbalance for the frame 6, and the parts carried thereby.

In order to take up wear between the frame 6 and its guide rod 4, so that lateral movement in the frame 6 is prevented, a take-up device is employed comprising preferably an integral extension or projection 12 on the frame coöperating with one face of the rod 5. The frame 6 also has an inclined surface 13 thereon which is substantially V-shaped in cross section, and on this inclined surface a slotted plate or member 14 is adjustable, so as to bear against the face of the rod 5 opposite that engaged by the projection 12. A bolt 15 passes through the slot of the plate 14 to hold the plate in its adjusted position on the inclined bearing 13. It is apparent that by shifting the plate 14 rearwardly on the inclined bearing 13, the rod 5 will be more firmly held between the plate 14 and the projection 12, and in this way prevent any lateral movement of the frame 6. The rod 5 is secured by a bolt 16 at its lower end, and by loosening this bolt the rod may be turned to present other portions thereof to the projection 12 and the plate 14 after the rod has been worn. In this way all lateral movement in the frame 6 may be eliminated, notwithstanding any wear on the guide 4 or in the take-up means. The frame 6 is provided with a slot 17 in which any tool may be introduced

and oscillated for the purpose of cooperating with the walls of the slot in order to produce the vibrations in the frame 6, for the purpose of shaking the core box supported by such frame.

5 The core box 18 may be secured by bolts 19 to a supporting member 20, the latter having a tube 21 on its upper side in which a rod 22 is secured by a bolt 23. The rod 10 22 extends rearwardly and projects into a forwardly-opening split sleeve 24 which, in turn, is mounted to turn about a horizontal axis 25, being held in different positions by a bolt 26 anchored in the frame 6 and operating in an arcuate slot 27 formed in the rear end of the sleeve 24. A clamping screw 28 passes through the sleeve 24 to connect the latter on opposite sides of the slot or split therein, and on this screw a thumb nut 20 29 operates in order to increase or decrease tension on the rod 22. It is apparent that the rod 22 may be turned in the sleeve 24 about a horizontal axis, so that the angular position of the core box with reference to the plate 2 may be changed. The nut 29 25 with the clamping bolt 28 serves to hold the rod 22 and the core box in the adjusted position. The angle of the core box, with reference to the bench plate 22, may be changed 30 in another direction by means of the horizontal axis 25, the bolt 26 serving to secure the sleeve 24 with the core box in the adjusted position.

The core box is filled with sand when it 35 lies in the position shown in Fig. 4, that is, with the box disposed upwardly, after which the core plate 30 is fitted thereover and the core box is inverted and moved toward the bench plate 1, so that the core 40 plate 30 rests on the bench plate. The core box is then withdrawn from the core 31 supported on the core plate, the usual vibration being imparted to the core box by means of an instrument vibrating in the 45 slot 17 or by other vibrating means.

From the foregoing it will be seen that there has been provided a core-making machine in which the core box is firmly held against any lateral movement which would 50 tend to destroy the cores during the with-

drawal of the core box. Any wear in the machine can be readily taken up without the necessity of employing new parts. The angle of the core box with reference to the bench plate may be readily changed.

55

What I claim as my invention and desire to secure by Letters Patent is:—

1. In a core making machine, a bench, a guide rod arranged in rear of said bench, a frame guided on said rod, a core-box supporting-member on said frame, a second guide, and an adjustable take-up device comprising a rigid projection on the frame cooperating with one face of the rear guide, an inclined surface on the frame, a slotted member cooperating with the inclined surface and also with the opposite face of the rear guide, and a bolt for securing the slotted member in its adjusted position on the inclined surface.

60

2. A core making machine comprising a bench, a split sleeve mounted at the rear of the bench to turn about a horizontal axis, means for securing said sleeve in its adjusted position, a rod fitted to turn in the 75 sleeve, means for clamping the sleeve on the rod, and a core box supported by the rod over the bench.

70

3. A core making machine comprising a bench, a core box, and means for supporting the core box so that the latter may turn about a horizontal axis in rear of the box and also about a horizontal axis at right angles to the first named axis.

80

4. A core making machine comprising a 85 base frame, a bench plate angularly adjustably secured to the base frame, a guide rising from the base frame in rear of the bench plate, a frame adjustable toward and from the bench plate on the guide, and a core box 90 angularly adjustable on said frame.

90

5. A core making machine comprising a bench, two rods rising in rear of the bench, one of said rods being rotatable, a frame guided on the other rod, a core box mounted 95 on said frame, and a take-up device cooperating with opposite sides of the rotatable rod.
